MOUTH-TO-MOUTH RESUSCITATOR

Robert A. Berman, Far Rockaway, N.Y., assignor to Medical Plastics, Inc., Jamaica, N.Y., a corporation of New York

Filed Aug. 26, 1958, Ser. No. 757,375
5 Claims. (Cl. 128—29)

The present invention relates to a mouth-to-mouth resuscitator and it particularly relates to a mouth-to-mouth resuscitator which is made of plastic material.

It is among the objects of the present invention to provide a novel mouth-to-mouth resuscitator which may be readily manipulated and will eliminate the necessity of physical contact between the mouth of the person being treated and the mouth of the person seeking to accomplish the resuscitation and which at the same time may be readily sanitized, and produced and stored under sanitary conditions.

Another object is to provide a simple, low-cost mouth-to-mouth resuscitator which will be readily effective without skilled or trained operators and which may be readily utilized with adults, children or infants and which will permit possible resuscitation action with assurance that the breathing operations of the respirator may be effectively and fully communicated to the person whose resuscitation is to be accomplished.

A still further object of the present invention is to provide a resuscitation apparatus in which the device will be of such low cost and of such inexpensive construction that it may be readily discarded after usage thereof and so that a supply of such mouth-to-mouth resuscitators may be kept on hand and readily assembled when needed for use with persons of varying mouth or head sizes and with the mouth pieces being readily adjustable and replaceable to fit the relative mouth sizes of the resuscitator as well as the person who is to be resuscitated.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objectives, it has been found most satisfactory, according to one embodiment of the present invention, to provide an elongated, concave, deep cup member, which will closely fit the periphery of the mouth of the resuscitating person as well as the person being resuscitated and which will not cause any undue pressure over the area while at the same time most effective use of the breathing apparatus of both persons involved is accomplished.

In the perfect form of the invention, the body of the cup is desirably flexible or of a molded, flexible polyethylene plastic material with the base of the cup and the rim of the cup being relatively rigid.

Each of the cups is desirably provided with a central nipple setting away therefrom and these nipples may be attached to a straight, rigid tube which will constitute the connection between the cups in the mouth-to-mouth resuscitator.

The cups are generally of such a size that they will extend well beyond the ends of the mouth and tend to have a resilient grip longitudinally across the mouth while they will only contact and exert slight pressure along the upper and lower edges of the mouth where it is backed up by the upper and lower teeth.

With the foregoing and other objects in view, the invention consists of the novel combination, construction and arrangements of parts as hereinafter more specifically

2

described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

FIG. 1 is a side perspective view of the mouth-to-mouth resuscitator showing end cups of about the same size.

10 FIG. 2 is a fragmentary transverse view taken along the line 2—2 of FIG. 1.

FIG. 3 is a transverse sectional view along the line 3—3 of FIG. 1.

15 Referring to FIGS. 1 and 3, there is shown a mouth-to-mouth resuscitator having the upper cup A, the lower cup B and the connecting tube C.

20 The upper cup A is shown as having a relatively flat base portion 10 with the rather short, elongated upwardly, curved side portions 11 and the deep or long end portions 12 which terminate in the circular extension 13.

25 The periphery of the ends of cup A have the out-turned lips 14 which are relatively thick and beveled off as indicated at 15 with the out-turned lip 14 and the enhanced thickness thereof tending to strengthen, and giving a fairly rigid structure with the flexibility being contained in the bottom wall 10, the end walls 12 and the side walls 11.

30 It will be noted by reference to FIG. 1 that the end walls 12 and the side walls 11 are quite bulged outwardly so as to enhance their flexibility.

35 The upper side edges 16 are provided with a thin, sharp lip at 17 (see FIG. 3) which will give less rigidity to the edges 16 than to the end edges or beads 14 but at the same time cause the flexibility to be restricted to the base or bottom 10, the side walls 11 and the end walls 12.

40 Desirably the end walls 12 are thicker than the side walls 11 or the bottom wall 10 and have less flexibility so that they will clamp on to the sides of the face beyond the ends of the mouth and tend to press the ends of the mouth together to open the lips.

45 The central portion 18 of the base is also given rigidity by the groove and ridges 19 which terminate in the shoulder 20 and the nipple 21.

50 The nipple 21 fits into the end 22 of the tube C with the end of the tube abutting the shoulder 20.

55 Normally the nipple 21 will be tapered slightly so that there is a jamb fit in the end 22 of the tube C by the nipple 21.

When the cup A has been forced into or connected with the end of the tube C, the nipple will be held firmly in position and the cups will be held on to the tube C unless strong pulling pressure is applied thereto.

55 The structure of the edge 16 is such that it may be stretched slightly upon forcing the side walls 12 and their end beads along the ends of the mouth.

60 The use of a relatively flexible polyethylene for the cups A and B, and a rigid plastic for the tube C, permits the resuscitator using the cup A to apply a flexing pressure through the cup B to the mouth of the person being resuscitated.

65 Although the cups are shown of the same size in FIG. 1, it is apparent that the lower cup may be of smaller or larger size to match the size of the mouth of the person being resuscitated whether it be an infant, child or adult.

70 Both the cups A and B may be readily changed and substituted, depending on the size of the mouth and face of the person involved in the mouth-to-mouth resuscitation.

When applied in a mouth-to-mouth resuscitation opera-

tion, the tube C will carry the pressure of the normally prone person with the flexing being taken up by the bottom walls 10 and primarily the side walls 11, with the end walls 12 serving primarily for clamping purposes across the ends of the mouth.

The upper and lower cups are desirably of substantially the same construction with both flexing primarily through the bottom wall 10 which may be made thinner than the end walls 12 and the side walls 11, and with the beads 14 at the ends of the cup and the beads 17 at the sides of the cup giving rigidity at the line of contact at the mouth of both persons in the mouth-to-mouth resuscitation.

It is apparent that the applicant has provided a simple, inexpensive, readily applied mouth-to-mouth resuscitative device.

The cups A and B and the tube C may be readily sterilized by placing them in hot water and different sizes may be utilized. If desired, the cups A and B may be turned at different angles better to accomplish the mouth-to-mouth resuscitation.

The particular mouth-to-mouth resuscitator disclosed in the present application may be used by anyone whether a professionally trained person, a layman or by a child or adult and it is particularly useful in case of mass casualties and in connection with civilian defense.

It is particularly useful in that it does not require insertion of a tube or a rod or passageway into the throat and since there is no likelihood of injury to the person whose resuscitation is necessary.

The tube C may be of cellulose acetate butyrate and it may be eight to twelve inches in length and it desirably should be rigid with only limited flexibility, if any.

The end cups A and B should be thinnest at their curved portions 10, 11 and 12 and thickest at their rim and center portions 14, 15, 16, 17, 18 and 19 with the cup portion in its intermediate areas at 10, 11 and 12 being of a more flexible material or having a thickness of one-third and one-half than the rims 15 and than the central portion 19.

The end cups A and B are relatively thin at their curved portions 11 in FIG. 3 and 12 in FIG. 2 and are thicker at their edge portions 13, 14 and 15 in FIG. 2 and 17 in FIG. 3.

The intermediate cup portions as indicated at 10, 11 and 12 have a more flexible material and they should have a thickness at 10, 11 and 12 which is about $\frac{1}{3}$ to $\frac{1}{2}$ the thickness of the material at the rims 14 and 15 of FIG. 2 and 17 of FIG. 3.

As a result the bottom and side walls 10, 11 and 12 will be relatively flexible as compared to the rim portions 14, 15, 16 and 17 which are relatively rigid.

The same is also true of the central portions at 18 and 19 which are relatively rigid as compared to the flexible walls 10, 11 and 12.

The cup portions which are primarily formed of the bottom walls 10 and the side walls 11 and 12 have a thickness of about $\frac{1}{3}$ to $\frac{1}{2}$ of the rim portions 14, 15, 16 and 17 and the central portions 18 and 19.

The dimensions may vary from one and one-half inches by two and one-half inches up to one inch by two and one-quarter inches and generally the cup should be of such a size so as to extend beyond the ends of the mouth by a dimension of one inch to two or three inches and above and below the mouth so that they will press against the gums about one-quarter to one-half inches above the teeth with the total dimension above the mouth being about one-quarter to one and one-half inches.

The cups A and B are desirably made of a polyethylene which is rigid in thick section but flexible in thin section.

While there has been herein described a preferred form of the invention, it should be understood that the

same may be altered in details and in relative arrangement of parts within the scope of the appended claims.

Having now particularly described and ascertained the nature of the invention, and in what manner the same is to be performed, what is claimed is:

1. A mouth-to-mouth resuscitator of transparent plastic material comprising two end cups of polyethylene and a connecting rigid plastic tube, said cups having bottom tapered rigid nipples telescoping inside of the ends of said rigid tube each of the cups having outwardly curved relatively-stiff bevelled-off edge bead contact portions extending around the outer periphery of the cups with elongated thick flexible end walls and short thin wide flexible side walls and thin flexible bottom walls and the nipples having a peripheral shoulder around the junction of the nipple and the cup for extra stiffness, said shoulders abutting the ends of the rigid tube, said nipples being open into the interior of the cups and into the tube and the cups being in communication with each other through the tube.

2. The resuscitator of claim 1, said bottom and short sides of said cups being made of relatively thin flexible polyethylene section and said end walls and contact lip and nipple being formed of relatively stiffer polyethylene sections so that there may be applied through said rigid tube a flexing of the cup with the ends of the walls serving for clamping purposes across the ends of the mouth and the flexing being taken up by the bottom and side walls.

3. The resuscitator of claim 1, in which the end cups are of polyethylene with the cup portions having a thickness of about one-third to one-half of the rim portions and said cups and tube being removable from one another for sterilizing purposes.

4. A three-piece mouth resuscitator formed of an intermediate straight rigid connecting tube and of laterally elongated rounded side and bottom end cups of a plastic sheet material rigid in thick section and flexible in thin section, said cups having thick rigid beads around the outer periphery thereof and connection nipples projecting from the bottom of the cups and telescoped with the ends of the connecting tube and having thin flexible curved side, end and bottom walls extending integrally between the beads around the outer periphery and the connection nipple, said nipples being open into the interior of the cups and into the tube and the cups being in communication with each other through the tube.

5. A three-piece mouth resuscitator all of washable and sterilizable plastic formed of an intermediate straight rigid connecting tube of cellulose acetate butyrate of 8 to 12 inches in length and of elongated rounded side and bottom end cups of polyethylene rigid in thick section and flexible in thin section, said cups having thick rigid beads around the outer periphery thereof and ridged connection nipples projecting from the bottom of the cups and telescoped with the ends of the connecting tube and having thin flexible curved side, end and bottom walls extending integrally between the beads around the outer periphery and the ridged connection nipple, said nipples

60 being open into the interior of the cups and into the tube and the cups being in communication with each other through the tube.
